UNITED STATES PATENT OFFICE.

THOMAS J. STURTEVANT, OF WELLESLEY, MASSACHUSETTS, ASSIGNOR TO STURTEVANT MILL COMPANY, OF BOSTON, MASSACHUSETTS, A CORPORATION OF MASSACHUSETTS.

CRUSHING-MILL.

1,360,465.

Specification of Letters Patent. Patented Nov. 30, 1920.

Application filed July 11, 1917. Serial No. 179,845.

To all whom it may concern:

Be it known that I, THOMAS J. STURTEVANT, a citizen of the United States, residing at Wellesley, county of Norfolk, and 5 State of Massachusetts, have invented an Improvement in Crushing-Mills, of which the following description, in connection with the accompanying drawings, is a specification, like characters on the drawings representing like parts.

The invention hereinafter described relates to crushing mills for reducing materials, and is of the general class shown in Letters Patent of the United States, No. 15 995,580, dated June 20, 1911; No. 1,000,457, dated August 15, 1911; and No. 1,105,713, dated August 4, 1914.

A mill of this class comprises a rotary anvil ring and crushing rolls mounted on 20 carriers which are pressed by springs to force the rolls toward the inner face of the ring to crush a stream of material fed between them and held to said ring by centrifugal force.

25 The thickness of this stream of material varies and sometimes contains abnormally large lumps. As a consequence, the rolls are permitted to move toward and from the ring, according to the varying thickness and 30 conditions of the stream of material. It is desirable to maintain substantially equal pressures on the rolls to produce uniform operation of the mill.

One of the objects of the invention is to 35 produce simple and effective means for pressing the rolls yieldingly outward toward the inner face of the ring, for transmitting pressure from one roll to another, and for equalizing pressure on the rolls.

40 Another object of the invention is to provide a simple mechanism for supporting and pressing the rolls toward the ring with provision permitting ready access to the parts of the mill for purposes of inspection and 45 repair.

With the aforesaid and other objects in view, the character of the invention will be best understood by reference to the following description of one good form of the invention shown in the accompanying drawings, wherein:

Figure 1 is a side elevation of the crushing mill shown herein as embodying the invention;

Fig. 2 is a vertical section through the mill 55 shown in Fig. 1;

Fig. 3 is a front elevation of the mill; and

Fig. 4 is a vertical section taken on line 4—4 of Fig. 2. 60

Referring to the drawings: The mill shown therein as embodying the invention comprises a base 1 supporting a casing 3 containing an anvil ring 5 having a concave inner crushing face 7 and mounted on a 65 spider 9 having a hub 11 fast on a shaft 13 journaled in bearings in standards 15 mounted on said base. The shaft has a pulley 17 fast thereon which may be driven by a belt (not shown) from a suitable source 70 of power.

A plurality of crushing rolls 19 may be mounted within the ring in opposition to the inner face thereof to crush material fed between them. These rolls are journaled on 75 carriers, in the present instance of the invention in the form of shafts 21 projecting laterally outward from the casing and mounted in boss bearings 23 integral with yokes 25 having ends journaled in bearings 27 mounted on the outer face of a head or door 29 movable to open and closed positions. To permit this movement of the door, it may be connected to the casing by hinges 31.

The roll carriers pivotally mounted on the 85 door as described will permit the rolls to move toward and from the inner face of the ring. Next will be described the means for pressing the rolls toward the ring. To accomplish this, a floating member common 90 to the carriers is provided, in the present instance of the invention in the form of a ring 33 encircling the carriers and located adjacent the outer face of the door in a plane substantially parallel to the plane of 95 the anvil ring. Suitable means may be provided to support said member, and in the present instance this is accomplished by a link 35 pivotally connected to said member adjacent the lower side thereof and projecting upwardly through an aperture in a rib or shoulder 37 on the door. This link is yieldingly supported by a coil spring 39 confined between said shoulder and a washer secured by a nut 41 on said link. Adjustment 100 of this nut 41 will permit the elevation of the member to be varied, as desired.

Each of the roll carriers is provided with

a link 43 pivotally connected thereto and projecting outwardly through a hole in the ring 33 sufficiently large to allow a certain amount of play of the link therein. A coil spring 45 encircles the link and is confined between a socket 47 on the outer periphery of the ring and a washer secured by a nut 49 on the link.

The construction is such that the springs, when properly tensioned, will react against 10 the outer periphery of the ring and operating through their links, will draw the carriers outward and press the crushing rolls toward the anvil ring against the stream of material fed between them.

15 This ring will desirably serve to transmit pressure from one roll to another and tend to equalize the pressures thereon. For example, if an abnormally large lump passes between the upper crushing roll and the 20 anvil ring, said roll will be moved inwardly, thereby causing its carrier to pull down on the link 43 and increase the tension on the spring 45. The latter will press more strongly against the ring 33 and thereby 25 thrust it downward against the tension of its supporting spring 39. Downward movement of the ring will increase the tension on the springs 45 for the lower roll carriers and thereby increase the pressure of the 30 lower rolls toward the anvil ring. Similarly, if either of the lower rolls moves inwardly, the ring 33 will move upwardly, and thereby increase the tension on the 35 spring for the upper roll and increase the pressure on the latter.

Gravity tends to move the upper roll downward away from the anvil ring and tends to pull the two lower rolls downward toward the anvil. It is desirable to provide all the rolls with equal pressures. The 40 springs 45 acting on the carriers for the rolls may have their tension adjusted to compensate for the effect of gravity thereon. This would require the tension of the 45 spring for the upper roll to be greater than the tension of the springs for the lower rolls.

It is desirable to limit the outward movement of the crushing rolls by the springs 50 45. To accomplish this, each of the links 43 may have a nut 50 thereon secured by a lock nut 50^a and serving as a stop for engaging the inner surface of the ring to prevent movement of the crushing rolls 55 outward beyond a predetermined point.

The crushing rolls should be drawn outward against the inner face of the anvil ring with sufficient force, so that they will lightly engage said ring and enable the latter to have enough traction on the rolls to rotate the same in starting the mill. The stop nuts preferably are so adjusted that they will permit this light pressure of the rolls against the anvil ring, but will become effective to limit substantial movement of

said rolls outward beyond the ring when the door is open and the rolls are swung away from the ring.

The roll carriers project through elongated apertures 51 in the door and are 70 provided with sliding plates 53 which follow the movements of the carriers, but are sufficiently large to cover said apertures and prevent escape of dust therethrough.

To feed material to the mill, it may be 75 provided with a hopper 55 delivering the material through a chute 57 mounted on the door to and between the anvil ring and one of the lower crushing rolls.

It will be noted that the rolls, their carriers, the equalizing ring, its supporting spring, and the springs and links for pressing the crushing rolls outwardly toward the anvil ring, are all mounted on the door. As a result, the door may be readily opened, 80 thereby withdrawing the rolls from the interior of the casing and exposing the anvil ring and parts carried by the door for convenient inspection, adjustment and repair.

It will be understood that the invention 90 is not limited to the specific embodiment shown, but that various deviations may be made therefrom without departing from the spirit and scope of the appended claims.

What is claimed is:—

1. A crushing mill comprising in combination, an anvil ring, crushing rolls opposed to the inner face of said ring to crush material between them, carriers for said rolls, and means including an equalizing ring located exteriorly of the anvil ring for transmitting pressure from one roll to another. 100

2. A crushing mill comprising, in combination, an anvil ring, crushing rolls opposed to the inner face of said ring, carriers for said rolls, and means including an equalizing ring encircling said carriers for transmitting pressure from one to another. 105

3. A crushing mill comprising, in combination, an anvil ring, crushing rolls opposed to the inner face of said ring, carriers for said rolls, an equalizing ring, and springs connected to said carriers and equalizing ring for pressing said rolls toward said anvil ring. 115

4. A crushing mill comprising, in combination, an anvil ring, crushing rolls opposed to the inner face of said ring, carriers for said rolls, and means including a floating ring for pressing said rolls toward said anvil ring. 120

5. A crushing mill comprising, in combination, an anvil ring, crushing rolls opposed to the inner face of said ring, carriers for said rolls, and means including a floating member encircling said carriers for pressing said rolls toward said anvil ring. 125

6. A crushing mill comprising, in combination, an anvil ring, crushing rolls opposed to the inner face of said ring, carriers for said rolls, a floating member disposed about said carriers, and spring means coöperating with said floating member and carriers for pressing said rolls toward said ring. 65
- 5 7. A crushing mill comprising, in combination, an anvil ring, crushing rolls opposed to the inner face of said ring, carriers for said rolls, and means to press said carriers outward toward said ring including spring means and a floating member 10 acting through said carriers and movable in a plane substantially parallel to the plane of said ring. 75
- 10 8. A crushing mill comprising, in combination, an anvil ring, crushing rolls opposed to the inner face of said ring, carriers for said rolls, and means to press said carriers outward toward said ring including a floating member acting through said carriers and movable radially of said ring. 80
- 15 9. A crushing mill comprising, in combination, an anvil ring, crushing rolls opposed to the inner face of said ring, carriers for said rolls, a floating member disposed about said carriers, spring means coöperating with said floating member and carriers for pressing said rolls toward said ring, and means to support said member. 85
- 20 10. A crushing mill comprising, in combination, an anvil ring, crushing rolls opposed to the inner face of said ring, carriage for said rolls, a floating member, spring means coöperating with said floating member and carriers for pressing said rolls toward said ring, and spring means to support said member. 90
- 25 11. A crushing mill comprising, in combination, an anvil ring, crushing rolls opposed to the inner face of said ring, carriers for said rolls pivotally mounted to permit said 95 rolls to swing toward and from said face, springs for pressing said carriers outward toward said ring, and a ring for positioning said springs. 100
- 30 12. A crushing mill comprising, in combination, a casing having a movably mounted door, an anvil ring in said casing, crushing rolls opposed to the inner face of said ring, carriers for said rolls mounted on said door, a ring carried by said door, and springs coöperating with said ring and carriers for pressing the rolls toward said anvil ring. 105
- 35 13. A crushing mill comprising, in combination, an anvil ring, crushing rolls opposed to the inner face of said ring, carriers for said rolls, an equalizing ring, links connected to said carriers, and springs coöperating with said equalizing ring and links for pressing said crushing rolls outward toward said anvil ring. 110
- 40 14. A crushing mill comprising, in combination, a casing having a door hinged thereon, an anvil ring mounted in said casing, crushing rolls opposed to the inner face of said ring, carriers for said rolls, an equalizing ring, and springs coöperating with said equalizing ring and carriers for pressing the rolls toward said anvil ring, said rolls, their carriers, said equalizing ring and springs being mounted on and movable with said door. 115
- 45 15. A crushing mill comprising, in combination, an anvil ring, crushing rolls opposed to the inner face of said ring, carriers for said rolls, an equalizing ring, means including a link and spring to support the said equalizing ring, and springs coöperating with the latter to press the rolls toward said anvil ring. 120
- 50 16. A crushing mill comprising, in combination, a casing having a movably mounted door, an anvil ring in said casing, crushing rolls opposed to the inner face of said ring, carriers for said rolls mounted on said door, an equalizing ring for said carriers, a link connected to the equalizing ring, a spring mounted on said door supporting said link, and springs coöperating with said equalizing ring and carriers for pressing the rolls toward said anvil ring. 125
- 55 17. A crushing mill comprising, in combination, a vertical anvil ring, crushing rolls opposed to the inner face of said ring, pivotally mounted carriers for said rolls projecting laterally outward beyond said ring, an equalizing ring movably supported adjacent said carriers, and springs coöperating with said equalizing ring and carriers for pressing said rolls toward said anvil ring. 130
- 60 18. A crushing mill comprising, in combination, an anvil ring, a support therefor rotatable on a fixed axis, crushing rolls opposed to the inner face of said ring, pivotally mounted carriers for said rolls, a ring encircling said carriers, and springs coöperating with said ring and carriers to press the rolls toward said anvil ring. 135
- 65 19. A crushing mill comprising, in combination, an anvil ring, crushing rolls opposed to the inner face of said ring, carriers for said rolls, an equalizing ring adjacent said carriers, spring means yieldingly connecting said equalizing ring and carriers for pressing said rolls outward toward said anvil ring, and stop means coöperating with said equalizing ring to limit said outward movement of said rolls. 140
- 70 20. A crushing mill comprising, in combination, an anvil ring, crushing rolls opposed to the inner face of said ring, a casing for said ring, a door for said casing carrying said rolls, an equalizing ring movably mounted adjacent said door, springs coöperating with said equalizing ring to press said

rolls outward toward said anvil ring, and means to limit outward movement of said rolls when said door is open.

21. A crushing mill comprising, in combination, an anvil ring, crushing rolls opposed to the inner face of said ring, carriers for said rolls, an equalizing ring adjacent said carriers, spring means forming

connections between the equalizing ring and carriers for pressing the rolls outward toward said anvil ring, and means to limit the outward movement of said rolls.

In testimony whereof I have signed my name to this specification.

THOMAS J. STURTEVANT.
